CLAIM

The ornamental design for an oral care device, as shown and described herein.

DESCRIPTION

FIG. 1 is a front, top, left side perspective view of an oral care device comprising a toothbrush holder, a mouthwash cup, and a toothpaste dispenser in accordance with another embodiment of the present design.

FIG. 2 is a front, bottom, right side perspective view of the oral care device shown in FIG. 1.

FIG. 3 is a front view of the oral care device shown in FIG. 1.

FIG. 4 is a rear view of the oral care device shown in FIG. 1.

FIG. 5 is a left side plan view of the oral care device shown in FIG. 1.

FIG. 6 is a right side plan view of the oral care device shown in FIG. 1.

FIG. 7 is a top side plan view of the oral care device shown in FIG. 1; and,

FIG. 8 is a bottom side plan view of the oral care device shown in FIG. 1.

In the drawings, the broken lines in the drawing figures illustrate environmental structure and form no part of the claimed design.
